(57) **CLAIM**

The ornamental design for a digitizer machine for use in a dental laboratory system, as shown and described.

DESCRIPTION

The article in which the design is embodied is a digitizer machine for scanning a dental model and is for use in a dental laboratory system.

FIG. 1 is a top and left side perspective view of a digitizer machine for use in a dental laboratory system showing our new design;

FIG. 2 is a top plan view thereof;

FIG. 3 is a top and right side perspective view thereof;

FIG. 4 is a left side elevation thereof;

FIG. 5 is a front elevation thereof;

FIG. 6 is right side elevation thereof;

FIG. 7 is a rear elevation thereof; and,

FIG. 8 is a bottom plan view thereof.
